UNITED STATES PATENT OFFICE.

EDWIN F. NORTHRUP, OF PRINCETON BOROUGH, NEW JERSEY.

METHOD OF AND APPARATUS FOR PRODUCING HIGH TEMPERATURES.

1,189,725.

Specification of Letters Patent.

Patented July 4, 1916.

Application filed October 8, 1915. Serial No. 54,789.

To all whom it may concern:

Be it known that I, EDWIN F. NORTHRUP, a citizen of the United States, residing in the borough of Princeton, county of Mercer, 5 and State of New Jersey, have invented a new and useful Method of and Apparatus for Producing High Temperatures, of which the following is a specification.

My invention relates to electric furnaces 10 and particularly those suitable for the production of high temperatures.

My invention resides in an electric furnace in which the resistor element, preferably of carbon or graphite, is confined in a 15 space to or from which gases cannot readily pass and in which the gas constitutes an atmosphere in which the resistor element is chemically in equilibrium, the gas being preferably generated within the furnace it- 20 self almost entirely from material forming no part of the resistor itself, particularly when of carbon or graphite, in which case the gas is of reducing character and consists of carbon monoxide and nitrogen, which be- 25 sides prolonging the life of the resistor renders the furnace as a whole suitable for certain treatments where oxidation is to be prevented.

My invention resides also in a resistor ele- 30 ment, preferably of carbon or graphite, prefer- ably tubular in form and so cut longitudinally as to produce a long path for current flow, making possible the use of relatively small currents and considerable voltage, par- 35 ticularly when the resistor is of carbon or graphite; and a further feature of my in- vention resides in means for mechanically strengthening a resistor element so formed as by inclosing the same between inner and 40 outer cylinders or tubes, preferably of carbon or graphite, with a filling of refractory material.

My invention resides also in electric fur- 45 nace structure whereby unusually high tem- peratures, for example 3000 degrees C. and higher, may easily be produced by con- 50 duction of current through a solid resistor, as of graphite or carbon, or through a resistor of gas or vapor by conduction that is not 55 that of an electric arc; and my invention resides in an electric furnace in which such 60 high temperatures may be produced by the

employment of such a resistor of solid material or of gas or vapor in co-operation with a resistor producing a lower temperature; 55 the stepping up of the temperature from that of the resistor producing the lower temperature to the temperature of the other resistor producing the higher temperature is termed by me heating in "cascade" and the 60 structure for producing the higher tempera- 65 ture is termed "cascade attachment," though it will be understood that my invention is not limited to the use of a structure pro- 70 ducing the higher temperature always in combination with a resistor producing a lower temperature.

My invention resides also in the method of 75 electrically producing heat and in the apparatus therefor hereinafter described and particularly pointed out in the claims.

For an illustration of some of the forms 75 my apparatus may take reference is to be had to the accompanying drawings, in which:

Figure 1 is a vertical sectional view, some parts in elevation, through an electric fur- 80 nace embodying my invention. Fig. 2 is a top plan view, on enlarged scale, of the heater unit of Fig. 1. Fig. 3 is a view, on small scale of the resistor element developed 85 or unrolled into a plane. Fig. 4 is a ver- 90 tical sectional view, some parts in elevation, of a heater unit suitable for producing very high temperatures and which may also be used as the cascade attachment in connection 95 with the furnace shown in Fig. 1. Fig. 5 is a top plan view of the heater unit shown in Fig. 4. Fig. 6 is a view of the resistor of Fig. 4 developed or rolled out into a plane. Fig. 7 is a diagrammatic view illustrating electrical connections which may be employed for supplying electric energy to the heater units. Fig. 8 is a diagrammatic view illustrating a system and apparatus for pro- 95 ducing very high temperatures by con- 100 duction of high frequency electric energy through a resistor of gas or vapor.

Referring to Figs. 1 to 3 inclusive, 1 re- 100 presents the outer furnace casing and 2 an inner furnace casing, both of which may be of metal or other suitable material, and be- 105 tween which is formed a compartment filled with any suitable material 3 of poor heat

conductivity, as for example, kieselguhr. The furnace bottom 4, which may be of metal, may be supported in any suitable manner as for example, upon the legs 5.

5 In the inner casing 2 is a mass 6 of refractory material of poor heat conductivity which may be a body of molded refractory material fitting within the casing 2 and adapted to closely surround the heater unit 10 structure. The body 6 may be made of a mixture of quartz sand and aluminum oxid or alundum and any suitable binder, as sodium silicate.

Disposed in the upper end of the casing 15 2 is the top 7 consisting of a block of material more or less refractory, as for example, alberene stone. A cover 8, which may be of metal, extends from the upper rim of the outer casing 1 to the block 7.

20 The resistor 9 is shown tubular in form and consists of any suitable material, as metal or carbon, and is preferably of graphite, such as pure Acheson graphite or regraphitized graphite. As shown in Figs. 25 2 and 3 the resistor tube 9 has the slits or cuts 10 completely through its wall extending from one end to near the other end, and the similar slits or cuts 11 extending from the lower end to near the upper end. As 30 seen in Fig. 3 this produces a considerable length of graphite conductor and of such an arrangement that the terminals are both at one end of the resistor and side by side. One of these terminals 12 is shown in Figs. 35 1 and 2 and the other, 13, is shown in Fig. 2, these terminals 12 and 13 being attached to the resistor at 12' and 13' Fig. 3.

Because of the long path provided for the 40 current through the resistor by the cutting or slitting referred to, the electric energy necessary to heat the resistor to a predetermined temperature may be supplied as a current of relatively small value and at a voltage or potential which is correspondingly higher than if the current path were 45 shorter or of greater cross section.

The cross section of the graphite or resistor material at the parts 14 where the slits or cuts 10 and 11 fail to pass completely 50 to the end of the resistor is preferably the same as the cross section at any other point throughout the current path, with the result that the resistor will become heated uniformly throughout its length, developing as 55 high a temperature at each end as at any point intermediate the ends.

The terminals 12 and 13 are of carbon or graphite, particularly when the resistor 9 is of carbon or graphite, and are attached 60 to the resistor ends by the graphite screws 15. Each terminal has a portion 16 extending upwardly through a hole in the block 7 and diminishing in diameter toward the top and having a hole 17 threaded to 65 receive the metal bolt 18 having the

head 19 which firmly secures to the extension 16 the metallic cap 20 which excludes air from the terminal and to which is clamped by the screws 21 the conducting lead 22 connecting to the binding posts 23 70 carried on the insulating member 24 supported upon the shell 1. A screw 25 is threaded into the top of the bolt 18 and clamps thereto an extension 26 on lead 22 clamped to the lead 22 by one of the screws 21. Beneath the bolt head 19 is disposed an insulating washer 27.

A carbon or graphite resistor formed as above described is more or less fragile. It is protected by an outer tube 28 of carbon or 80 graphite and an inner tube 29 of carbon or graphite, the clearance space between the resistor 9 and the tubes 28 and 29 being filled with aluminum oxid 30 or other suitable refractory insulating material, as for 85 example, zirconium oxid. The material 30 extends nearly to the top of the tubes 28 and 29 above the top of the resistor 9, and is surmounted by refractory cement 30^a as a stopper. To reduce likelihood of breakage 90 of the terminals 12 and 13 from the resistor 9 each terminal is provided with a pin or screw 31 of lavite or other suitable material embedded in the material 30^a. The tube 29 may have a bottom as indicated at 32. 95

Within the refractory material 6 is a graphite lining tube 33. The tubes 28 and 33 are cut away on one side near their tops in the vicinity of the resistor terminals 12 and 13. 100

Within the tube 28 is a removable crucible tube 34 generally of graphite but which may be of any other suitable material, as for example, Marquardt porcelain. Tube 34 forms the furnace chamber in which the 105 temperature developed by the resistor 9 is utilized, and within the chamber 34 is placed the material to be heated. The tube 34 has near its top an internal annular channel 35 into which may be expanded the 110 ends of tongs for lifting the tube 34 out of the furnace through the hole 36 in the block 7 after the removal of the stopper 37, of alberene stone or other suitable material, having the holes 38 and 39, the former forming 115 means for inspecting the furnace chamber and the latter for introducing pyrometric means.

Either direct or alternating current may be passed through the resistor 9 to raise its 120 temperature and thereby raise the temperature within the furnace chamber.

In Fig. 7 40 and 41 represent conductors connected to a source of alternating current which may be connected to the primary *p* of the transformer *T* by closing the switch 42. The transformer *T* is illustrated, by way of example, as a step-down transformer whose secondary *s* delivers current when the switch 43 is closed to the right through the con- 130

ductors 44 and 45 to the resistor terminals 12 and 13.

The furnace structure above described is such that the passage of gases into and out of the heating chamber is prevented or restricted and the access of air to the resistor 9 is similarly prevented or restricted. 70

Carbon or graphite is readily attacked by oxygen when above a red heat or 640 degrees C., and therefore to procure suitable 10 length of life of the carbon or graphite resistor it must be effectually protected from oxidation, since the temperature it must produce is far above that of a red 15 heat. This may be accomplished by recourse to a vacuum or by passing through the furnace a protecting gas, for example hydrogen. In my furnace however, I have recourse to neither of these expedients, but 20 produce a reducing gas or a gas neutral with respect to carbon or graphite, by the action of the oxygen of the air which may be in the furnace upon the graphite surrounding or protecting the resistor itself. 25 When this graphite reaches a suitable temperature the oxygen of the air confined in the inner compartment 2 of the furnace combines with the carbon of the graphite to produce carbon monoxide gas, leaving in 30 the furnace a mixture of such gas with the remnant nitrogen of the air. These gases are practically the only ones remaining in the furnace, with the result that the resistor is effectually protected from oxidation, even though carried to very high 35 temperature.

The more completely the resistor is enclosed in carbon or graphite, as by the structure illustrated, the more completely 40 will the neutral or reducing atmosphere be produced by such graphite other than that of the resistor, and any gas reaching the resistor while at high temperature will be chemically neutral with respect to the 45 resistor graphite.

While the production of a reducing or neutral atmosphere within the furnace is important as to protection of the resistor itself, the production of such an atmosphere 50 has the further advantage of serving as a reducing atmosphere which is necessary and desirable in many furnace methods. It will be understood therefore that by a structure of the character described, and by 55 preventing free passage of air into the furnace, the furnace automatically produces a gas which protects its resistor and which simultaneously serves as a reducing atmosphere suitable for protecting from oxidation 60 any material heated within the furnace. And when graphite only is present in the furnace structure, no gases or vapors are generated in the furnace which might contaminate or injuriously affect any material 65 treated in the furnace.

A furnace structure of the character above described lends itself readily to an interchangeability of all parts of the furnace, and a worn out heater unit may quickly be removed and a new one inserted. The 70 furnace parts are practically indestructible with the exception of the heater unit, and it has a long life, is relatively inexpensive and is the only part of the furnace that must be renewed. 75

By a structure as of the character above described working temperatures of 1600 degrees C., or thereabout are easily attained and higher temperatures are obtainable, but at the expense of reduced life of heater 80 unit. The temperature produced within the heating chamber is such that when containing a crucible a perfect black body condition or temperature is available.

For the production of still higher temperatures a structure of the character illustrated in Figs. 4, 5 and 6 may be employed in combination with the structure hereinbefore described, though it will be understood that the structure of the character 90 illustrated in Figs. 4, 5 and 6 is not limited to its use in such combination, and in accordance with my invention its use in any useful relation is contemplated. 95

Referring to Figs. 4, 5 and 6, 46 is a tubular structure of alberene stone or any other suitably refractory material within which are disposed the carbon or graphite electrodes 47 and 48 formed by cutting vertically through, as at 49, a carbon or 100 graphite tube. The electrodes 47 and 48 are held by screws 50 in firm contact with the inner walls of the member 46 and in electrical contact with the metallic members 51 and 52 constituting parts of the terminals 53 and 54 provided with the binding 105 screws 55 and 56. The electrodes or terminals 47 and 48 have cut in them to considerable depth the annular channels 57 and 58 in which are disposed the ends 59 and 60 110 of resistor 62. Graphite screws 61 clamp the electrodes 47 and 48 snugly and in good electrical contact with the resistor ends 59 and 60. The resistor 62 is a tube of 115 graphite longitudinally slit or cut on opposite sides, as indicated at 63 and 64 from the upper end of the resistor tube to near its lower end, the lower end being circumferentially continuous at 65 to form a connection between the two halves or sides of the 120 resistor.

Secured to the tubular head 46 by screws 66 is a graphite jacket tube 67 surrounding the electrodes 47 and 48 and the resistor 62 and having in its bottom a plug 68 of 125 graphite held in place by the transversely extending graphite pin 69. The plug 68 near its upper end is reduced in diameter, as indicated at 70, and upon the shoulder so formed rests the graphite tube 71 surround- 130

ing and spaced from the resistor 62, the tube 71 serving to confine the radiant heat to its interior and as a shield to protect the furnace parts outside of tube 71. The plug 68 has a central hole extending to the pin 69 in which is disposed the crucible tube 72 of graphite or other material which rests upon the pin 69 and extends upwardly within the resistor 62. As shown, the crucible tube 72 may have a bottom 73 mid-way 5 of its length so that the crucible proper is that part of the tube 72 above the bottom 73. This member may be reversed so that the lower portion may extend into the resistor 10 and the upper portion rest upon the pin 69. The result is that the member 72 as illustrated forms a double crucible, either end of which may be employed when the other is destroyed or otherwise rendered unsuitable. 15 20 By removal of the pin 69 the plug 68 and the crucible tube 72 and tube 71 may be readily removed by withdrawing them downwardly out of the tube 67. And a new resistor element may be introduced by re- 25 moving the outer tube 67 and inserting the same in place in the electrodes 47 and 48 and tightening screws 61.

This structure may be used by itself for producing high temperatures by connecting 30 the terminals 53 and 54 to any suitable source of current, direct or alternating, whereupon current will flow from one of the terminals, as 53, through the electrode or terminal 47, thence through the resistor 35 62 to the other electrode or terminal 48 and thence to the terminal 54, the current in traversing the resistor 62 raising its temperature.

For the production of very high temperatures, as upward of 3000 degrees C., which 40 I have accomplished by this apparatus, as evidenced by the fact that I have melted pure tungsten therewith, which late investigations show melts at approximately 3327 45 degrees C., the resistor 62 should be disposed in a neutral or non-oxidizing gas which may be delivered into the interior of the apparatus or which may be therein formed as by oxidation of graphite in the presence of the 50 small amount of air originally present.

A convenient method of using this structure is to place it in an atmosphere of neutral or non-oxidizing gas, and this may conveniently be done by inserting the same into 55 the apparatus shown in Fig. 1, sliding the unit of Fig. 4 into the interior of the tube 29 from which the tube 34 has been withdrawn. Current is then first thrown on to the resistor 9 by throwing the switch 43, Fig. 7, 60 into the right hand position until a temperature of 1400 degrees C. or higher is attained; before which time the carbon monoxide and nitrogen atmosphere will have been produced which will protect not only the 65 resistor 9, but also the resistor 62. After

the resistor 9 has produced the temperature mentioned, the switch 43 is thrown over into the left hand position, whereupon current will flow from the transformer secondary 8 through the switch 43 and the conductors 74 70 and 75 to the terminals 53 and 54 of the inner heating unit. Inasmuch as the resistor 62 is protected by non-oxidizing atmosphere, its temperature may be raised to practically that which is the vaporization 75 point of graphite at atmospheric pressure. And such temperature is easily attained and quickly by dissipating sufficient electrical energy in the resistor 62.

By the above operation there is a preheat- 80 ing or preliminary heating by the resistor 9 and then the temperature is stepped up to a still higher temperature in and by the resistor 62 and this stepping up of the temperature has been termed by me heating in 85 "cascade" and the attachment or arrangement of Fig. 4 has been termed a "cascade attachment."

I have found also that in place of conduction through a solid, as graphite, herein- 90 before referred to, I can produce very high temperatures by conduction of electric energy through gases or vapors at atmospheric pressure or higher. For this purpose apparatus of the character illustrated in Fig. 8 95 may be employed. Within the hollow member 76, which may be of graphite or other suitable material, is disposed a solid or tubular member 77 of any suitable material, for example graphite, spaced from the in- 100 terior wall of the member 76, the intervening space being filled with gas or vapor, such as metallic vapor. The member 76 may have a cover 78 of refractory material, such as alberene stone, through which extends a 105 tube 79, as of Marquardt porcelain, communicating with the interior of the member 77. The member 77 may have the removable screw threaded bottom plug 80 upon which may rest the crucible 81. By preheating the 110 gas or vapor to a temperature upward of 1400 degrees C. conduction will occur through the gas or vapor at atmospheric pressure when the members 76 and 77 are connected to a source of current, of suitable 115 potential, either direct or alternating. The current passed through the gas or vapor may be of such magnitude as to cause the gas or vapor to rise still higher in temperature and indeed to very high temperatures, with the 120 result that the member 77 is brought to a high temperature, the limit of which is believed to be the vaporization temperature of the graphite of member 77. This high temperature may be utilized for heating materials placed within the member 77 or within a crucible 81 in the member 77.

The space between members 76 and 77 may contain refractory material in whose interstices is the gas or vapor for current 125 130

conduction. Or the member 76 may have a refractory lining, as a tube of Marquardt porcelain. By thus starting with a gaseous or vapor phase of matter to obtain high temperature by direct electric conduction through the gas or vapor, there is no further state beyond the gaseous or vaporous into which matter can pass under elevation of temperature, and hence the heater medium is indestructible and therefore offers a means of producing the highest obtainable temperatures.

For the gas through which the conduction occurs I have employed air and also carbon monoxid, which develops automatically in a graphite furnace in a closed container. I have also used the vapors of mercury and bismuth; and vapors of other metals and compounds may be used.

When using direct or alternating current I have found that with a constant vapor or gas temperature an increase of potential is accompanied by a still more rapid increase of current, and that with a constant applied potential an increase of current is accompanied by an increase of temperature.

For preliminarily raising the temperature of the gas or vapor to the above mentioned conductive state, I have placed the members 76 and 77 within the furnace illustrated in Fig. 1. Therefore the arrangement of Fig. 8 may also be considered a cascade attachment, though it is to be understood that it may be used in other relations, and that my invention is not limited to use as a cascade attachment.

When using direct current or alternating current of low frequency for raising the temperature of a gas or vapor, there is more or less tendency to localization of conduction between very restricted areas upon the members 76 and 77 to form an arc, the conduction being then arc conduction through a very restricted region and not well distributed over the surfaces of the members 76 and 77 as is desirable. To overcome this tendency to arcing the energy passed between the members 76 and 77 through the gas or vapor may be in the form of high frequency alternating current or in the form of high frequency electrical oscillations. The choice of high frequency alternating current or electrical oscillations insures against the formation of an arc, because the current of high frequency alternating current or of electrical oscillations will not select an isolated or restricted conducting path of low resistance so readily as it will avoid a conducting path of high inductance. Accordingly, by the use of high frequency alternating current or of electrical oscillations the energy will be conducted between the members 76 and 77 quite uniformly over their surfaces.

For the production of the alternating cur-

rent of high frequency any suitable means may be employed, as for example, the high frequency alternators some of which are now known capable of delivering current at a frequency as high as 100,000 cycles per second.

In Fig. 8 an arrangement is shown for passing between the members 76 and 77 the energy of high frequency oscillations. T is any suitable induction coil or transformer, the terminals of whose secondary 81 are connected to the spark gap 82 connected in circuit with the condenser 83, which may be adjustable if desired, and the inductance 84, which may be adjustable if desired, and which forms the primary of an oscillation transformer whose adjustable secondary 85 has its terminals connected to the conductors 86 and 87, the former connected with member 76 and the latter with the tungsten or other wire 88 extending through tube 79 and connecting with member 77.

As well understood in the art of electrical oscillations there will be produced in the circuit 82, 83, 84 high frequency oscillations whose periodicity is largely dependent upon the capacity of the condenser 83 and the inductance of the winding or coil 84. As shown the transformer 84, 85 may be a step down transformer, so that the voltage impressed upon the members 76 and 77 may be lower than that of the oscillation producing circuit and the current greater than that in the oscillation producing circuit.

In place of the oscillation producing circuit including a spark gap any other suitable oscillation producing means may be employed, such, for example, as one employing an arc producing sustained oscillations, or any other continuously oscillating circuit may be employed or the high frequency oscillations may be generated by a dynamo-electric generator.

It will be understood that high potentials are not necessary for the operation of the gas or vapor heating device, for potentials as low as 100 volts or lower may be employed to secure substantial conduction through the gas or vapor.

Inasmuch as the conducting surface of the member 77 is smaller than that of the member 76 the member 77 will attain the higher temperature because per unit area there is a greater dissipation of energy on the member 77 than there is on the member 76.

For the electrode, as 77, may be used refractory material such as alundum. And as a liner for the member 76 may be used Marquardt porcelain or other suitable material. Even when using these materials alundum and Marquardt porcelain I have procured conduction through the intervening gas.

What I claim is:

1. An integral tubular resistor having

- neighboring slots extending from opposite ends and forming the resistor material into a current path extending backwardly and forwardly longitudinally.
5. 2. An integral tubular resistor having a slot extending throughout its length, a plurality of neighboring slots extending from opposite ends and forming the resistor material into a current path extending backwardly and forwardly longitudinally, and current connections on opposite sides of and adjacent said first named slot.
10. 3. An integral tubular resistor having neighboring slots extending from opposite ends and forming the resistor material into a current path extending backwardly and forwardly longitudinally, and terminals disposed side by side and at the same end of the resistor.
15. 4. An integral tubular graphite resistor having neighboring slots extending from opposite ends and forming the resistor material into a current path extending backwardly and forwardly longitudinally.
20. 5. An integral tubular graphite resistor having a slot extending throughout its length, a plurality of neighboring slots extending from opposite ends and forming the resistor material into a current path extending backwardly and forwardly longitudinally.
25. 6. An integral tubular graphite resistor having neighboring slots extending from opposite ends and forming the resistor material into a current path extending backwardly and forwardly longitudinally, and graphite terminals disposed side by side and at the same end of the graphite resistor.
30. 7. An integral tubular graphite resistor having neighboring slots extending from opposite ends and forming the resistor material into a current path extending backwardly and forwardly longitudinally, and graphite terminals disposed side by side and at the same end of the graphite resistor, said terminals projecting beyond the end of the tubular resistor.
35. 8. In combination, a slotted tubular resistor having neighboring slots extending from opposite ends thereof and forming the resistor material into a current path, a tubular member surrounding said tubular resistor and spaced therefrom, a second tubular member within said tubular resistor and spaced therefrom, and means forming said resistor and said tubular members into a unit.
40. 9. In combination, a slotted tubular resistor having neighboring slots extending from opposite ends thereof and forming the resistor material into a current path, a tubular member surrounding said tubular resistor and spaced therefrom, a second tubular member within said tubular resistor and spaced therefrom, and refractory insulating material disposed in the space between said resistor and tubular members.
45. 10. An integral tubular resistor having neighboring slots extending from opposite ends and forming the resistor material into a current path extending backwardly and forwardly longitudinally, the cross section of the current path at the ends of the tubular resistor having a cross section such that the passage of current therethrough produces a temperature substantially equal to the temperature produced intermediate the ends of the tubular resistor.
50. 11. An electric heater unit comprising a tubular resistor, a tubular member fixed within said resistor and spaced therefrom, and refractory material in the space between said resistor and said tubular member.
55. 12. A heater unit comprising a tubular resistor having neighboring slots extending from opposite ends thereof, a tubular member surrounding said tubular resistor and spaced therefrom, a tubular member disposed within said tubular resistor and spaced therefrom, and refractory material disposed in the spaces between said resistor and said members.
60. 13. A heater unit comprising a tubular resistor, tubular members within and surrounding said resistor and spaced therefrom in fixed relation thereto, and refractory material disposed in the space between said resistor and said members.
65. 14. A heater unit comprising a tubular resistor, tubular members within and surrounding said resistor and spaced therefrom, refractory material disposed in the space between said resistor and said members, said members having greater length than said resistor, and refractory material extending across the end of said resistor between said members.
70. 15. A heater unit comprising a tubular resistor, tubular members within and surrounding said resistor and spaced therefrom, refractory material disposed in the space between said resistor and said members, and a tubular member of refractory material disposed within said inner tube.
75. 16. An electric heater unit comprising a tubular graphite resistor, a tubular member of graphite fixed within said resistor and spaced therefrom, and refractory insulating material disposed between said resistor and said member.
80. 17. An electric heater unit comprising a slotted tubular graphite resistor, neighboring slots extending from opposite ends to form a current path extending backwardly and forwardly longitudinally, graphite tubes surrounding and within said tubular resistor and spaced therefrom, and refrac-

- tory material disposed in the space between said resistor and said members.
18. An electric heater unit comprising a tubular graphite resistor, tubular members of graphite within and surrounding said resistor and spaced therefrom in fixed relation thereto, and refractory insulating material disposed in the space between said resistor and said members.
19. An electric heater unit comprising a tubular graphite resistor, a tubular member of graphite surrounding and spaced from said resistor, refractory insulating material between said resistor and said member, and a terminal secured on the outer side of said resistor, said tubular member being cut away in the vicinity of said electrode and spaced therefrom.
20. An electric heater unit comprising a tubular resistor of graphite, a graphite terminal secured thereto, refractory material covering said resistor, and a member attached to said terminal and anchored in said refractory material.
21. In an electric furnace, a heater unit comprising a tubular resistor, tubular members within and surrounding said resistor and spaced therefrom, refractory material disposed in the space between said resistor and said members, refractory material disposed at the ends of said resistor between said tubular members, a mass of refractory material, and a hollow liner therefor adapted to receive said heater unit.
22. An electric furnace comprising a hollow mass of refractory material, a heater unit disposed within said mass and comprising a graphite resistor and a graphite inclosure for said resistor, and a graphite lining in said mass of refractory material.
23. An electric furnace comprising a hollow mass of refractory material, a heater unit comprising a graphite resistor and graphite inclosing said resistor, a terminal on said resistor disposed within said refractory material, a graphite lining in said refractory material receiving said heater unit, said graphite lining being cut away in the vicinity of said terminal and spaced therefrom.
24. An electric furnace comprising a mass of refractory material, a heater unit disposed in said mass and comprising a tubular resistor and tubular members within and surrounding said resistor and spaced therefrom, and a tubular member disposed within said inner tubular member and constituting the hot zone of the furnace.
25. The combination with a resistor capable of chemical reaction with a gas, of refractory members spaced apart, refractory material in the space between said members, said resistor inclosed in said refractory material, said members heated by said resistor and being of material capable of reacting with said gas to produce a gas which is chemically neutral with respect to said resistor.
26. The combination with a resistor capable of chemical reaction with a gas, of refractory members spaced apart, refractory material in the space between said members, said resistor inclosed in said refractory material, said members heated by said resistor and being of material similar to that of said resistor and reacting with said gas to produce a gas which is chemically neutral with respect to said resistor.
27. The combination with a resistor of carbon or graphite, of carbon or graphite members spaced apart, refractory material between said members in which said resistor is inclosed, said members being raised in temperature by said resistor to react with surrounding gas to produce an atmosphere surrounding said members neutral with respect to said resistor.
28. The combination with a tubular resistor of carbon or graphite, of tubular members of carbon or graphite surrounding and within said resistor and spaced therefrom, a removable carbon or graphite tube within the inner of said members, a mass of refractory material, a lining therein receiving the outer of said members, and a member having an aperture through which said tube may be withdrawn.
29. The combination with a chamber, of a resistor for heating the same, and a second resistor in said chamber for producing a temperature different from that produced by said first named resistor.
30. The combination with a chamber, of a resistor for heating the same, and a second resistor in said chamber producing a temperature higher than the temperature produced by said first named resistor.
31. The combination with a chamber, of a resistor for heating the same, a second resistor in said chamber for producing a temperature different from that produced by said first named resistor, and means for enveloping said second resistor in an atmosphere with respect to which it is chemically neutral.
32. The combination with a chamber, of a resistor for heating the same, a second resistor in said chamber for producing a temperature different from that produced by said first named resistor, and means for producing an atmosphere chemically neutral with respect to said resistors.
33. An electric furnace comprising a plurality of resistors, one of said resistors constituting a preheater for another of said resistors.
34. An electric furnace comprising carbon or graphite resistors, means for passing current through one of said resistors to preheat the furnace, and means for passing cur-

- rent through another of said resistors for stepping up the temperature.
35. In an electric furnace, a heater unit comprising a carbon or graphite resistor, a carbon or graphite member heated thereby for producing a non-oxidizing atmosphere, and a second heater unit comprising a carbon or graphite resistor disposed in said non-oxidizing atmosphere and heated by said first named resistor.
36. In an electric furnace, a heater unit comprising a carbon or graphite resistor, a carbon or graphite member heated thereby for producing a non-oxidizing atmosphere, a second heater unit comprising a carbon or graphite resistor disposed in said non-oxidizing atmosphere and heated by said first named resistor, means for passing current through said first named resistor, and means for passing current through said second resistor to raise its temperature at higher rate.
37. A heater unit comprising a longitudinally slotted tubular resistor of carbon or graphite, terminals slotted to receive the ends of said resistor, a tubular member inclosing said resistor, a removable bottom for said tubular member, and a hollow member supported on said bottom and projecting into said resistor.
38. A heater unit comprising a longitudinally slotted tubular resistor of carbon or graphite, terminals slotted to receive the ends of said resistor, a tubular member inclosing said resistor, a removable bottom for said tubular member, a hollow member supported on said bottom and projecting into said resistor, and a tubular member supported by said bottom and intervening between said resistor and said first named tubular member.
39. The combination with a heating chamber, of means for raising the temperature thereof, means for producing higher temperature disposed in said chamber and comprising a longitudinally slotted tubular resistor of carbon or graphite, terminals slotted to receive the ends of said resistor, a tubular member inclosing said resistor, and a removable bottom for said tubular member.
40. Electrical heating apparatus comprising a resistor of gas or vapor at atmosphere pressure or higher, and a source of energy alternating or fluctuating at a frequency preventing arc conduction through said gas or vapor.
41. Electrical heating apparatus comprising a resistor of gas or vapor at atmospheric pressure or higher, a source of high frequency oscillations, and means for conducting the energy of said oscillations through said gas or vapor.
42. The method of producing heat electrically, which consists in preheating a gas or vapor at atmospheric pressure or higher, and passing electric energy of high frequency therethrough.
43. Electric heating apparatus comprising electrodes separated by gas or vapor, a source of current connected to said electrodes, one of said electrodes being hollow to form a heating chamber.
44. A cascade furnace comprising a low temperature resistor, a heating chamber raised in temperature thereby, and an independent heater unit disposed in said chamber and removable therefrom comprising a closed chamber, and a graphite resistor therein for producing higher temperature.
45. A cascade furnace comprising a low temperature resistor, a heating chamber raised in temperature thereby, an independent heater unit disposed in said chamber and removable therefrom comprising a closed chamber, a graphite resistor therein for producing higher temperature, a source of energy, and switching mechanism for connecting either of said resistors to said source of energy.
46. A cascade furnace comprising a heater unit, said unit comprising a resistor and a heating chamber adapted to be raised in temperature thereby, and a second heater unit disposed in and removable from said heating chamber and comprising a resistor for producing temperatures higher than said first named resistor, and a heating chamber raised in temperature by said second resistor.
47. A cascade furnace comprising heater units one of which is contained within another, one of said heater units comprising a tubular resistor, a tubular refractory member disposed within and raised in temperature by said resistor and adapted to receive another of said heater units, said other of said heater units comprising a resistor for producing higher temperatures than said first named resistor, and a hollow member constituting a heating chamber.
- In testimony whereof I have hereunto affixed my signature this 6 day of October, 1915.

EDWIN F. NORTHRUP.
